ELECTRIC LAMP

Herbert E. Plishker, Morristown, N.J., assignor to Westinghouse Electric Corporation, East Pittsburgh, Pa., a corporation of Pennsylvania

Filed July 17, 1959, Ser. No. 56,824

Term of patent 14 years

(Cl. D26—8)

FIG. 1.

FIG. 2.

FIG. 3.

Fig. 1 is a front perspective view of an electric lamp, showing my new design;

Fig. 2 is a side elevational view; and

Fig. 3 is a top plan view thereof.

The dominant features of my new design reside in the portions shown in full lines.

I claim:

The ornamental design for an electric lamp, substantially as shown and described.
